UNITED STATES PATENT OFFICE.

HERBERT McNULTA, OF BLOOMINGTON, ILLINOIS.

RHEOSTAT.

SPECIFICATION forming part of Letters Patent No. 516,217, dated March 13, 1894.

Application filed May 1, 1893. Serial No. 472,641. (No model.)

To all whom it may concern:

Be it known that I, HERBERT McNULTA, a citizen of the United States, residing at Bloomington, McLean county, Illinois, have invented 5 certain new and useful Improvements in Electrical Resistances, of which the following is a specification, reference being had to the accompanying drawings, in which—

Figure 1 is a top or plan view. Fig. 2 is a 10 sectional view on line 2—2 of Fig. 1. Fig. 3 is a side elevation. Fig. 4 is a plan view of one of the plates. Fig. 5 is an enlarged detail, being a vertical section through a portion of the resistance; and Figs. 6 and 7 are 15 views similar to Figs. 4 and 5, showing a modified arrangement.

My invention relates to electrical resistances, and particularly to that class commonly known as contact resistances. 20 The objects of my invention are to provide a new and improved resistance in which adequate means will be provided for cooling the surfaces of the plates, to provide for the expansion incident to the heating of the plates, 25 and to otherwise improve the construction of resistances of this class. I accomplish these objects as hereinafter specified and as illustrated in the drawings.

That which I regard as new will be set forth 30 in the claims.

In the drawings,—8 indicates one of the resistances, which consists of plates 9 arranged in two rows, as shown in Fig. 1. The plates 9 of each row are successively in contact with 35 each other, but are spaced a short distance apart, which arrangement is provided for by swaging in each plate three or more projections 10, thereby providing corresponding recesses 11 on the opposite side of such plate. 40 The projections 10 upon one plate fit into the recesses 11 in the next plate, and when the plates are secured together a compact body is secured.

As above stated, the plates 9 are arranged 45 in two rows, and are secured together by end pieces 12—13, which are united by a bolt 14 which passes between the two rows of plates 9, as shown in Fig. 1. The end pieces 12—13 are connected to connecting bars 15—16 respectively, to which bars other similar resistances may be connected, thereby forming a 50 battery of resistances.

17—18 indicate the end plates of the rows of plates, which end plates are provided with ears 19 bent at right angles to the main body 55 of the plates to adapt them to fit upon the end pieces 12—13, as shown. Between the end plates and the end pieces are inserted strips 20 of insulating material, such as mica, to insulate the plates 9 from such end pieces. 60 The end plates 17 at one end of the rows of plates are provided with projections 10 and the end plates 18 at the other ends of said rows are provided with depressions 11, to provide for causing said plates to fit snugly 65 against the adjoining plates.

To provide for the expansion of the plates 9 due to the heat generated by the passage of the current through them, the bolt 14 is provided at its ends with springs 21, which bear 70 against the head and nut of the bolt and the adjacent portions of the end pieces 12 or 13. As the plates 9 expand the springs 21 will permit the end pieces 12—13 to separate slightly, and will cause them to approach 75 each other as the plates become cool again. By this construction the pressure of the plates upon each other will be substantially uniform at all times, and the resistance will not, therefore, be caused to vary materially by ordinary variations in the current passed through the plates. By separating the plates as shown air is permitted to pass freely between them, thereby preventing over-heating.

The end plates 17—18 are also provided 85 with ears 22, by means of which the connections with the electric wires may be made. As shown in Fig. 3, one or more of the intermediate plates may also be provided with an ear 22, by means of which the number of 90 plates through which the current is passed may be varied as desired.

In Figs. 6 and 7 I have shown modified plates, in which,—in addition to the projections 10 above described,—three smaller projections 23 are provided, thereby forming corresponding depressions 24 in the opposite side of the plate. The depressions 24 are also in triangular form, forming a triangle equal to that formed by the projections 10. 100 The arrangement is such that in setting up the resistance the projections 10 of one plate will lie in the depressions 24 of the next plate. The projections 23 do not project far enough

to touch the surface of the adjacent plate. By this construction the plates 9 are spaced a greater distance apart than in the construction shown in Figs. 4 and 5, and the possibility of the flat surfaces of the plates being moved into contact with each other owing to the expansion caused by the passage of an extraordinary current through the resistance, is thereby prevented.

10. I do not wish to limit myself to providing each plate with three contact projections, as the number may be varied if desired. I prefer, however, to use three.

An important advantage in my improved 15 resistance lies in the fact that its construction is very inexpensive, since the plates 9 may be very rapidly stamped out and are immediately ready for assembling to form the resistance.

That which I claim as my invention, and 20 desire to secure by Letters Patent, is—

1. In an electrical resistance, the combination with a series of plates, each of said plates having projections adapted to lie in contact with an adjacent plate, of means for binding said plates together, substantially as described.

2. In an electrical resistance, the combination with a series of plates, each of said plates having a series of projections upon one face

30 and a series of indentations in the other face, of devices for binding said plates together, substantially as described.

3. In an electrical resistance, the combination with a series of plates, each of said plates 35 having a series of projections upon one face and a series of coincident indentations in the other face, the projections upon one plate being adapted to fit into the indentations in the adjacent plate, of means for binding said 40 plates together, substantially as described.

4. An electrical resistance, consisting of end pieces, a series of plates insulated from the end pieces and spaced a distance apart so that air can circulate between the plates, means 45 for electrically connecting the plates, and a

bolt connecting the end pieces, substantially as described.

5. An electrical resistance, consisting of a series of plates held together by a binding device and locked in engagement one to the other against independent lateral movement in any direction in planes parallel with the adjacent surfaces of the plates, substantially as described.

6. An electrical resistance, consisting of a 55 pile of plates each of which contacts with an adjacent plate by contact projections, substantially as described.

7. An electrical resistance, consisting of a series of plates engaged with one another and 60 yieldingly held together by a binding device, substantially as described.

8. In an electrical resistance, the combination with a series of plates in contact with each other, of yielding devices binding said 65 plates together, whereby a substantially constant pressure upon said plates will be maintained, substantially as described.

9. In an electrical resistance, the combination with a series of plates arranged in rows, 70 and end pieces at the ends of said rows, of a bolt extending between the rows of plates and connecting said end pieces, substantially as described.

10. In an electrical resistance, the combination with a series of plates arranged in rows, 75 and end pieces at the ends of said rows, of a bolt connecting said end pieces, and a spring upon said bolt, whereby expansion of said plates will be permitted, substantially as described.

11. An electrical resistance plate consisting of a plate 9 having a series of projections 10 upon one face, and a series of depressions in the other face, substantially as described.

HERBERT McNULTA.
